THROW-OFFS FOR ROTARY PRINTING PRESSES

Hans J. Luehrs, Westerly, R. I., assignor to C. B. Cettrell & Sons Company, Westerly, R. I., a corporation of Delaware

Application June 28, 1954, Serial No. 439,562

9 Claims. (Cl. 101—182)

This invention is directed to certain improvements in "throw-offs" for rotary printing presses and especially in individual "throw-offs" for multi-color rotary typographical printing presses.

In the conventional plate cylinder "throw-offs" wherein the form rolls remain stationary while the cylinder "throws" off and into contact with the form rolls, excessive ink is deposited on the "high" as well as the "low" portions of the plate. The first sheets through the press after a "throw-off" will be spoiled, and frequent time consuming wash-ups on the plates are necessary to minimize this spoilage.

One object of my invention is to provide means for eliminating the above objectionable condition by providing individual means to simultaneously "throw" both the plate cylinder and the form rolls "on" and "off".

A further object is to provide means whereby the ductor motion will also be turned "on" and "off" simultaneously with the throws of the plate cylinder and form rolls.

Another object, when this "throw-off" is applied to multi-color printing presses, is to provide individual throws timed in sequence in order to print the first sheet or repeat of a web when "throwing on" and to completely print the last sheet or repeat of the web when "throwing-off"; without depositing ink on any exposed tympan surface.

Another object, when the "throw-off" is applied to multi-color printing presses, is to provide each color unit with a combined plate cylinder, form roll, and ductor motion "throw," automatically activated in timed relation to the impression cylinder and the other color units; and in addition to also provide an individual ductor motion "throw" for each color unit, activated conveniently and selectively at will.

Another object is to provide means for "throwing on" a set of form rolls, in coordination with their plate cylinder, in such a manner as to establish contact between the impression cylinder and the plate cylinder, and to establish contact between the plate cylinder and its form rolls simultaneously at the end of the "throw-on" movement.

Another object is to provide means to "throw-off" a set of form rolls, in coordination with their plate cylinder in such a manner as to break contact between the impression cylinder and the plate cylinder and to break contact between the plate cylinder and its form rolls simultaneously at the beginning of the "throw-off" movement, whereby ample clearance will be established between the impression and plate cylinder and between the plate cylinder and its form rolls when in "off" position.

Another object is to provide a ductor "throw-off" arranged in coordination with its plate cylinder and form roll "throw," in such a manner as to activate the ductor motion and feed the ink when the plate cylinder and form rolls are on "on" position; or to inactivate the ductor

2

motion when the plate cylinder and form rolls are on "off" position.

Another object is to have each color unit, with its combined plate cylinder, form roll, and ductor "throw," activated automatically in timed relation to the impression cylinder and to the other color units, and, in addition, to individual hand-operated "throws," have each color unit with its combined plate cylinder, form roll, and ductor "throw" activated conveniently and selectively at will as a unit.

Another object is to provide means, in combination with the plate cylinder, form roll, and ductor "throw," identical roller sockets which can be mounted either as form roll sockets within the above combination, or as distributor roll sockets; having, in both cases, individual "throw-off" means independent of the "throw" for the plate cylinder, form roll, and ductor.

A practical embodiment of my invention is represented in the accompanying drawings, in which:

Fig. 1 represents, in side elevation, a diagrammatic view of a six-color rotary printing press;

Figs. 2 and 2a represent a detail side view of one of the color units with the several elements in the positions they assume when in their printing position;

Figs. 3 and 3a represent a detail plan view of the elements shown in Figs. 2 and 2a at one side of the press;

Fig. 4 represents a detail side view of the fluid pressure controlled, operatively connected elements, shown in their position to inactivate the ductor roll; together with the individual manually operated elements for inactivating the ductor roll;

Fig. 5 represents a detail view showing the said individual manually operated elements in their ductor roll inactivating position;

Fig. 6 represents a detail view taken in the plane of the line VI—VI of Fig. 5, looking in the direction of the arrows;

Fig. 7 represents a detail side view of the elements for throwing two of the four form rolls "on" and "off" contact with their plate cylinder;

Fig. 8 represents a similar view of the elements for throwing the other two form rolls "on" and "off" contact with their plate cylinder;

Fig. 9 represents a detail section taken in the plane of the line IX—IX of Fig. 7, looking in the direction of the arrows;

Fig. 10 represents a detail section taken through one of the form rolls in the plane of the line X—X of Fig. 2a, looking in the direction of the arrows;

Fig. 11 represents a detail section taken in the plane of the line XI—XI of Fig. 10, looking in the direction of the arrows;

Fig. 12 represents a detail section taken in the plane of the line XII—XII of Fig. 10, looking in the direction of the arrows;

Fig. 13 represents a detail section taken in the plane of the line XIII—XIII of Fig. 10, looking in the direction of the arrows;

Fig. 14 represents a detail section taken in the plane of the line XIV—XIV of Fig. 10, looking in the direction of the arrows;

Fig. 15 represents a detail perspective view of one of the distributor sockets, the several elements being separated from one another;

Fig. 16 represents a detail view of the socket and its adjacent elements taken in the plane of the line XVI—XVI of Fig. 2, looking in the direction of the arrows, and

Fig. 17 represents a detail section taken in the plane of the line XVII—XVII of Fig. 16, looking in the direction of the arrows.

As all of the printing units are alike in construction

and operation, I have chosen to show and describe only one of the printing units with its throw off mechanism for the plate cylinder, form rolls and ductor.

The impression cylinder is denoted by 1, the plate cylinder by 2 and its shaft by 3. The roll stand is denoted by 4.

The inking mechanism which is carried by the roll stand includes the following elements:

The ink fountain 5, the fountain roll 6, the oscillating ductor roll 7 and its arm 8 fast on the rock shaft 9. 10 Another arm 10 is fast on the rock shaft 9, which is provided with a roller 11 held against the face of a rotary cam 12 by the usual longitudinal yielding spring 13 connected on its upper end to an arm 14 fast on the rock shaft 9. The ductor roll 7 serves to transfer the ink 15 from the fountain roll 6 to the distribution rolls 15, 16 which, in turn, transfer the ink to the distribution rolls 17, 18 rotatively mounted in the sockets 19, 20.

The ink cylinder 21 carried by the rotary shaft 22 receives the ink from the distribution rolls 17, 18 and 20 transfers the ink to the upper and lower distribution rolls 23, 24, rotatively mounted in the sockets 25, 26. These rolls 23, 24 transfer the ink to the upper and lower vibrator rolls 27, 28 mounted on the shafts 29, 30. The upper form rolls 31, 32 serve to transfer the ink from 25 the upper vibrator roll 27 to the plate cylinder 2; and the lower form rolls 33, 34 to serve to transfer the ink from the lower vibrator roll 28 to the said plate cylinder 2.

The end sockets 35, 36 of the upper form rolls 31, 32 swing on the upper vibrator roll shaft 29; and the end 30 sockets 37, 38 of the lower form rolls 33, 34 swing on the lower vibrator roll shaft 30.

Endwise movable bars 39 operatively connect the arms 40, 40* and 41, 41* of the form roll sockets 35, 37; and endwise movable bars 43 operatively connect the arms 44, 44* and 45, 45* of the form roll sockets 36, 38.

The means for simultaneously "throwing-off" the plate cylinder 2, the form rolls 31, 32, 33, 34 and the ductor roll 7, is constructed, arranged and operated as follows:

An air cylinder 46 has its piston rod 47 pivotally connected to a rock lever arm 48 fast on a sleeve 48* mounted on the throw-off rock shaft 49, which rock shaft is provided at each end with a rock lever arm 50 operatively connected through an adjusting screw 51 to a projection 52 on the eccentric bearing 53 for the plate cylinder shaft 3. The rotative movement of the eccentric bearings 53 serve to throw the plate cylinder 2 "on" and "off" contact with the impression cylinder 1. At one end of this throw-off rock shaft 49 within the frame 54 there is provided a lever arm 55, which is connected by a link 56 to a projection 57 on a sleeve or strap 58 mounted on the eccentric bearing 53 within a circumferential groove 59.

Another projection 60 from this strap 58 has an open groove 61 which receives (when the roll stand 4 is moved to its operative position) a roller 62 mounted on the end of one lever arm 63 fixed to the form roll throw-off shaft 64. The other arm 65 of this lever is connected to the ductor roll throw-off mechanism as will be hereinafter described.

This shaft 64 has also fixed thereto, at each end thereof, a lever provided with two oppositely directed arms 66, 67 having longitudinal slots 68, 69 for receiving blocks 70, 71 carried by the bars 39 and 43 respectively.

The mechanism for simultaneously "throwing-off" the ductor roll with the plate cylinder and form rolls, is shown as constructed, arranged and operated as follows:

The lever arm 65 is engaged at 72 to one arm 73 of a rock lever mounted on the shaft 22, the other arm 74 of said lever being connected at 75 to the upper end of a longitudinally movable rod 76, which is yieldingly held in position by a coil spring 77; the lower end of this rod 76 is arranged to be brought into position to inactivate the ductor roll 7 by providing its shaft 9 with a lever arm 78, which is fast to rock with the ductor roll arm 8 and the 75

cam operated arm 10. This arm 78 may be provided with a roller 79 arranged in position to be engaged by the said rod 76 when the rod is moved downward by movement of the rock lever arm 74.

The independently operated means for inactivating the ductor roll 7 is shown as comprising the following elements: a hand lever 80 is fast on a rock shaft 81. A cam 82 is also fast on the rock shaft 81. When the lever 80 is in its lower position, as shown in Fig. 2, the raised portion of the cam 82 will be out of the path of the roller 79 of the ductor cam arm 78. When this hand lever 80 is raised to its other position, the raised portion of the cam 82 is brought into blocking engagement with the roller 79, thus inactivating the ductor roll 7.

A spring mounted detent 83 serves to yieldingly hold the levers 63, 65 and 66, 67 in either their "on" or "off" position to prevent the accidental over-travel of the roller 62 on the end of the lever arm 63, and thus ensure its engagement with the open groove 61 in the strap 58.

As all of the pairs of end sockets for the form rollers are the same, one of the sockets, i. e., the socket 35 for the form roller 31 will only be specifically described as follows:

The eccentric stud 84 serves to firmly clamp the socket 35, the block 85 and the block 86 to the seat 87 by means of a spring 88. The eccentric stud 84 has a stop 89 which allows the stud to be rotated 180° only. This partial rotation serves to throw the socket 35 and its form roller "on" and "off" contact with the plate cylinder 2 by means of the eccentric 90, block 91, and engaging block 86 in a direction imposed to the unit by pins 92. Adjusting screws 93 and 94 are provided for initially setting the form roll 31 for proper contact with the plate cylinder 2 and the vibrator roll 27.

The arc 95 indicates the swinging movement of the form roll 31 around its vibrator roll 27. The straight line 96 indicates the movement of the form roll 31 when the stud 84 is rotated through its 180°. The straight line 97 indicated the movement of the form roll 31 by the adjusting screw 93. The straight line 98 indicates the movement of the form roll 31 by the adjusting screw 94.

It will thus be seen that all of the form rolls have two independent throws and two independent adjustments.

As all of the pairs of end sockets for the distributor rolls are the same, one of these sockets, i. e., the socket 19 for the distributor roll 17 will only be specifically described, as follows:

An eccentric stud 99 firmly clamps the socket 19, the block 100 and block 101 to the frame 4, by means of the spring 102. The eccentric stud 99 has a stop 103 which allows the stud to be rotated 180° only. This partial rotation serves to throw the socket 19 and distributor roll 17 "on" and "off" contact with the ink drum 21 and roll 15, by means of the eccentric 104, block 105 and engaging block 101 in a direction as imposed to the unit, by pins 106. Adjusting screws 107 and 108 are provided for initially setting the distributor roll 17 for proper contact with the ink drum 21 and ink roller 15.

The straight line 109 indicates the movement of the distributor roll 17 by the 180° rotative movement of the eccentric stud 99. The straight line 110 indicates the movement of the distributor roll 17 by the adjustment of the screw 107. The straight line 111 indicates the movement of the distributor roll 17 by the adjustment of the screw 108. It will thus be seen that all the distribution rolls have one independent throw and two independent adjustments.

In operation, when the several elements of the assembly are in their operative positions, as shown in Figs. 2, 2a, and it is desired to throw the said elements out of their operative positions, the procedure will be as follows: The air cylinder 46 is caused through its connections to throw the plate cylinder 2 out of contact with the impression cylinder 1, by the rotative movement of the

eccentric bearings 53 in which the shaft 3 of the plate cylinder is mounted. At the same time the rotative movement of the straps 58 will rock the lever arms 63, 65 and the lever arms 66, 67 to move the bars 70, 71 in a direction to swing the form rolls 31, 33 anti-clockwise and the form rolls 32, 34 clockwise, out of contact with the plate cylinder 2. At the same time the lever arm 65 will swing the lever arms 73, 74 to move the rod 76 downwards to cause the lower end of the rod to block the roller 79 on the depending ductor lever arm 78 and thus prevent the ductor roll 7 to be oscillated by its rotary cam 12 through the roller 11 and its lever arm 10.

From the above description, it will be seen that when it is desired to throw in the plate cylinder 2 and the form rolls 31-34 and to unblock the ductor roll 7, the several elements of the throw out assembly are operated by the air cylinder 46 to simultaneously throw the elements into the coacting positions shown in Figs. 2 and 2a. The form roll sockets 35-38 and the distribution roll sockets 19, 20 and 25, 26 may then be manually adjusted to bring their rolls into proper positions to produce the best results.

When it is desired to simultaneously throw out the plate cylinder, the form rolls and the ductor roll, the several elements are operated by said air cylinder through the various elements to turn the eccentric bearings 53 to move the plate cylinder out of contact with the impression cylinder 1; to swing the form rolls away from their plate cylinder; and, through the levers 63, 65 and 73, 74, to move the bar 75 to block the depending arm 76 of the ductor roll 7.

While I have shown my invention in connection with a multi-color typographic rotary printing press, I do not wish to be limited to the type of press, nor to the number of printing units.

By providing an independently manually operated means for throwing "off" and "on" the ductor roll, it will be seen that this result may be accomplished even when the roll stand is in its retracted position.

It will be seen that the plate cylinder, form rolls and ductor of each color printing unit may be thrown "on" and "off" in timed sequence with the other printing units, and that also each such unit may be thrown "on" and "off" by manually and selectively controlled power.

It will also be seen that the form and distribution roll sockets which are of uniform basic structure, having means to individually throw these sockets with their rolls "on" and "off" in a selected direction by a single manual movement for each socket; automatic locking devices being employed in addition to the two direction adjusting elements for the initial setting of said rolls.

It is evident that various changes may be resorted to in the construction, form and arrangement of the several elements, without departing from the spirit and scope of my invention, and hence I do not intend to be limited to the particular embodiments herein shown and described.

What I claim is:

1. In a rotary typographical web printing press, a fixedly mounted impression cylinder, a coacting throw-off plate cylinder, form rolls therefor, a ductor roll, and a common power means operatively connected to the plate cylinder, the form rolls and ductor roll and operable to simultaneously throw "off" or "on" the plate cylinder and its form rolls and to inactivate or activate the ductor roll.

2. In a rotary typographical web printing press, a fixedly mounted impression cylinder, a coacting throw-off plate cylinder, form rolls therefor, a ductor roll, a common power means operatively connected to the plate cylinder, the form rolls and ductor roll and operable to simultaneously throw "off" or "on" the plate cylinder and its form rolls and to inactivate or activate the ductor roll, and the individual manually operated means for independently inactivating or activating said ductor roll.

3. In a multi-color rotary typographical web printing press, a fixedly mounted impression cylinder surrounding the impression cylinder, coacting throw-off plate cylinders, an ink distribution for each plate cylinder including form rolls and a ductor roll, and a common power means operatively connected to a selected plate cylinder, its form rolls and ductor roll and operable to simultaneously throw "off" or "on" the selected plate cylinder and its form rolls and to inactivate or activate the ductor roll.

4. In a multi-color rotary typographical web printing press, a fixedly mounted impression cylinder, coacting throw-off plate cylinders surrounding the impression cylinder, an ink distribution for each plate cylinder including form rolls and a ductor roll, a power means operatively connected to a selected plate cylinder, its form rolls and ductor roll and operable to simultaneously throw "off" or "on" the selected plate cylinder and its form rolls and to inactivate or activate the ductor roll, and individual manually operated means for independently inactivating or activating said ductor roll.

5. In a rotary typographical web printing press, a fixedly mounted impression cylinder, a coacting throw-off plate cylinder, form rolls, a ductor roll and a common power means operatively connected to the plate cylinder, the form rolls and ductor roll and operable to simultaneously throw "off" or "on" the plate cylinder and its form rolls and to inactivate or activate the ductor roll, comprising a plate cylinder throw off shaft, a form roll throw off shaft, devices operatively connecting the power means to the plate cylinder throw off shaft, devices operatively connecting the plate cylinder throw off shaft to the form roll throw off shaft, and ductor roll controlling devices operatively connected to said form roll throw off shaft.

6. In a rotary typographical web printing press, a fixedly mounted impression cylinder, a coacting throw-off plate cylinder, its shaft, form rolls and a ductor roll, and power means operable to throw "off" or "on" the plate cylinder and form rolls and to inactivate and activate the ductor roll comprising, eccentric bearings for the plate cylinder shaft, devices operatively connecting said plate cylinder throw off shaft to said power means and said eccentric bearings, devices including a strap rotatively mounted on one of said eccentric bearings operatively connecting the plate cylinder throw off shaft to the form roll throw off shaft, and ductor roll controlling devices rotatively connected to the said form roll throw off shaft.

7. In a rotary typographical web printing press, a fixedly mounted impression cylinder, a coacting throw-off plate cylinder, eccentric bearings therefor, a strap rotatively mounted on one of said bearings, upper and lower pairs of form rolls, rocking supports therefor, a ductor roll, a rocking support therefor, and a common power means operable to simultaneously throw "off" or "on" the plate cylinder and its form rolls and to inactivate and activate the ductor roll comprising, devices operatively connecting the eccentric bearings to the power means, devices operatively connecting the said form roll rocking supports to the power means, and devices for blocking and unblocking the ductor roll, operatively connected to said strap.

8. In a rotary typographical web printing press, a fixedly mounted impression cylinder, a coacting throw-off plate cylinder, eccentric bearings therefor, a strap rotatively mounted on one of said bearings, upper and lower pairs of form rolls, rocking supports therefor, a ductor roll, a rocking support therefor, and power means operable to simultaneously throw "off" or "on" the plate cylinder and its form rolls and to inactivate and activate the ductor roll comprising, a plate cylinder throw off shaft and rock levers thereon, operatively connecting the eccentric bearings to the power means, a form roll throw off shaft and levers thereon, operatively connected to said strap and to the 75 rocking supports for the form rolls, and a stop rod for

said ductor roll rocking supports, operatively connected to said form roll throw off shaft.

9. In a rotary typographical web printing press, a fixedly mounted impression cylinder, a coacting throw-off plate cylinder, a ductor roll, upper and lower pairs of form rolls, separate swinging supports for each form roll, a form roll throw off shaft, a rock lever thereon, two rods, one rod operatively connected to one form roll support of each pair of rolls and to one arm of the said rock lever, the other rod being connected to the other form roll support 10 of each pair of rolls and to the other arm of the said rock lever, and a common power means operatively connected to the plate cylinder to throw the plate cylinder "off" or "on" and also operatively connected to said form roll rock shaft to throw the form rolls "off" or "on," and 15

operatively connected to the ductor roll and operable to inactivate and activate the said ductor roll.

UNITED STATES PATENT OFFICE
CERTIFICATE OF CORRECTION

Patent No. 2,836,116

May 27, 1958

Hans J. Luehrs

It is hereby certified that error appears in the printed specification of the above numbered patent requiring correction and that the said Letters Patent should read as corrected below.

Column 6, lines 2 and 3, strike out "surrounding the impression cylinder" and insert the same after "cylinder" in line 4; line 15, for "a power" read -- a common power --; line 68, for "and power" read -- and common power --.

Signed and sealed this 14th day of October 1958.
